UNITED STATES PATENT OFFICE.

SCHUYLER R. SCHAFF, OF LOUISVILLE, KENTUCKY.

APPOINTMENT-ANNOUNCER.

1,137,427.

Specification of Letters Patent. Patented Apr. 27, 1915.

Application filed December 8, 1914. Serial No. 876,029.

To all whom it may concern:

Be it known that I, SCHUYLER R. SCHAFF, a citizen of the United States, and resident of Louisville, in the county of Jefferson and State of Kentucky, have invented certain new and useful Improvements in Appointment-Announcers, of which the following is a specification.

This invention relates to certain improvements in apparatus designed to call attention to the arrival of a predetermined time by giving a signal and to exhibit, if desired, memoranda indicating or reminding a person of the character of the appointment to be kept or the work to be done at that time.

In carrying out my invention, I provide a suitable member adapted to advance either continuously or intermittently at a uniform rate and adapted to receive the desired memoranda, and means for operating a signal upon the arrival of the portion of the number bearing the memoranda at a predetermined point along its path of travel.

In the preferred embodiment, I employ a strip of paper of sufficient width to permit the names of persons, places or events, or other memoranda serving as a reminder in regard to appointments or the like, or other matters to be written, stamped, or otherwise applied thereto, and this strip is of such length that a time period of considerable length, such for instance as a week, is required for it to pass through the machine. The paper is marked to indicate the subdivisions of time, such as days, hours, and, if desired, minutes, and the mechanism for advancing the paper is such that each indicated time on the strip arrives at a predetermined point in its path of travel at that time. Means are provided for perforating, embossing, or otherwise affecting the character or contour of the paper opposite the memoranda written thereon, and suitable alarm or signaling mechanism is employed so that the arrival of that portion of the paper at a predetermined point will cause the operating of the signal.

Reference is to be had to the accompanying drawings showing certain forms which my invention may assume and in which similar reference characters indicate corresponding parts in the several views.

In these drawings, Figure 1 is a vertical longitudinal section through a device constructed in accordance with my invention;

Fig. 2 is a top plan view thereof; Fig. 3 is a transverse section on the line 3—3 of Fig. 2; Fig. 4 is a perspective view of an alternative form and Fig. 5 is a detail of a slight modification of the construction shown in Fig. 4.

In the form shown in Figs. 1, 2 and 3, I employ a casing including a suitable platform or base 10, side walls 11 and 12 and a top wall 13. This top wall serves as a support for the strip of paper 14 so that the latter may be readily written upon or have data applied thereto by a stamp or other marking device. The strip of paper, which may be of a width nearly equal to the width of the casing, is advanced over the top wall 13 by suitable mechanism, but preferably either continuously or intermittently at a uniform rate. A roll of paper 15 is mounted, preferably within the casing, on suitable supports 16 and delivers the paper through a slot to the upper surface of the casing top 13. An end wall 17 adjacent to the roll may be hinged or otherwise secured in place so as to permit it to be readily lifted and a fresh roll inserted whenever desired. At the opposite end of the casing is a drum 18 which engages with the paper to advance the latter as the drum rotates. A small friction roller may bind the paper to the surface of the roll at one point so as to produce this result, or the paper may have a series of perforations 19 adapted to receive teeth, pins or spurs 20 on the periphery of the drum. Various means may be employed for rotating this drum at a very slow rate of speed. As shown, the drum is keyed to a shaft 21 having one end projecting through the end wall 12 of the casing and provided with a suitable handle or handwheel 22. At the other end a worm wheel 23 is connected to the shaft by a clutch 24. A drive shaft 25 has a worm 26 engaging with the worm wheel. Any suitable source of power may be employed and properly governed for rotating the shaft 25 at the desired speed. This may be in the form of a small electric or fluid operated motor or an electric clock, but as shown, I employ a spring motor in the form of a clock 27, which latter may have the ordinary hands and dial for indicating time or may comprise nothing more than an escapement-controlled spring motor.

As previously indicated, the character of the motor, the size of the drum and the character of the driving connections are so pro-

portioned to the spacing of the indications of time on the strip 14 that these indications in passing a predetermined, stationary point will correspond to the time of day, in addition to or independent of the indication given by the hands and dial of the clock and therefore the latter may be omitted if desired.

For operating the signal or alarm at the predetermined time, I provide in the specific form shown in Figs. 1, 2 and 3, a small paper perforator 29 in the form of a spring pressed punch which may be depressed and cut from the paper a small piece, either at the extreme margin, or at any desired distance therefrom. As shown, the punch operates at a slight distance from the edge of the paper and serves to form a round hole 30. Within the case and so positioned that it may enter the hole 30 as the latter reaches a predetermined point 32 on one of the two guides 28, beneath which the edges of the paper pass, there is mounted a circuit closing member 31 in the form of a piece of spring metal. The circuit closing member may rise as the hole reaches the point 32 and in rising may come in contact with the other terminal. The ringing of the bell as a result of the closing of the circuit will attract attention to the device and upon examining it, the memoranda on the paper, opposite to the hole 30, which caused the closing of the circuit, will remind the person as to the particular appointment that is to be kept at that particular time.

It is evident that a person may use the device for only his appointments or that a large number of people in an office may all use the same device and the latter may be in charge of one employee, such for instance as an office boy or telephone girl, whose duty it will be to advise other employees of the arrival of the time at which they are to be notified and to remind them of the memoranda which had been placed on the paper strip opposite the predetermined time.

As shown, a portion of the paper covering a time interval of several hours is exposed so that anyone glancing at the strip may see ahead as to what has been set down for the next few hours thereafter. If it is desired to mark on the strip memoranda in regard to matters several days ahead or on a portion of the paper not directly opposite the perforator, the paper may be readily advanced independently of the clock work. To permit this, I provide means for disengaging the worm wheel and drum so that the latter may be turned independently of the worm wheel and therefore independently of the clock work or other driving mechanism. As shown, I employ a clutch 24 which is normally in operative position, but which may be drawn to inoperative position by a

suitable handle 36. With the clutch out, the drum may be freely rotated by the handle 22 and the strip of paper advanced or returned as desired. To prevent the ringing of the alarm or signal at such times, I may provide any suitable means for breaking the electric circuit and this means may be directly connected to the clutch so that when the latter is out the circuit will be broken. I have shown merely a simple form of knife switch 37 on the side of the casing which is to be operated independently of the clutch.

The paper may be rewound in the proper coiled form, after the paper has been advanced to write memoranda thereon, and the returning of the paper to its proper position in respect to the driving mechanism may be readily secured by bringing the time indication on the strip, corresponding to the correct time of day, opposite to the point 38. Accuracy may be secured by making the clutch 24 in the form of a one-tooth clutch with accurately fitting or beveled engaging parts so that if an attempt be made to return the clutch to operative position when the strip is a slight distance from the correct position, the error will be corrected and the parts brought to proper registry.

In the specific form above described, I employ an electric bell and a circuit closer, but it is of course evident that this is not essential as other forms of signaling or alarm mechanism may be employed. Under some circumstances, I might employ a visible signal instead of an audible one and this might be in the form of an electric light or in the form of an arm or pointer raised or moved to indicating position at the proper time.

To avoid all complication and objections which might arise through the use of electric current, storage batteries and the like, and which might interfere with the free transporting of the devices from one point to another about the office, I may employ a signaling device operated solely by mechanical means. In Fig. 4, I have shown a cam wheel 40 supported on one side wall of the casing and normally tending to rotate in one direction by means of a spring 41. A bell 42 may have a pivoted striker 43 with one end in the path of the cam so that as the cam rotates the striker will be intermittently raised and then permitted to strike the bell. For controlling the rotation of the cam, I may provide a small bell crank lever 44 pivoted to the casing and having one arm 45 resting upon or contacting with the paper in the path of the perforations 30^a in the latter and having the other arm 46 in the path of certain studs, pins or stops on the hub of the cam wheel.

As shown, I provide stops 47 and 48, both of which may be duplicated around the hub.

The stops are so positioned that the cam is normally prevented from rotating by the engagement of one of the stops 47 with the arm 46 of the lever. As a perforation in the 5 paper reaches the arm 45 of the lever, the end of the latter is permitted to drop into the perforation and the other arm 46 of the lever will swing out of the path of the stop 47, and into the path of a stop 48. The stops 10 are spaced circumferentially so as to permit the cam to rotate a limited distance under the influence of the spring. This rotation should be sufficient to permit the striker 43 to drop off a cam projection and sound the 15 signal. As soon as the perforation passes the arm 45, the arm 46 is moved out of the path of the stops 48 and into the path of the next of the stops 47 and the cam rotates to lift the striker. If it is desired to repeat the 20 signal several times there need be only one stop 47 and one stop 48, but a plurality of gong lever operating projections are employed as shown. If only a single gong lever operating projection be formed on the 25 cam then there would only be a single stop 47 and a single stop 48.

I have shown the lever arm 45 provided with a roller which may enter a perforation 30^a of the paper, but it is of course evident 30 that the end of the lever may be formed in any other desired manner so as to accomplish the desired result. In Fig. 4, I have shown the gong operating mechanism spaced at some distance from the drum 18 whereas 35 in Fig. 5 I have shown the drum provided with an annular groove 50 adapted to come directly beneath the perforations and the bell crank lever is shown as resting upon the paper directly over the groove. 40 Instead of having a paper perforator directly on and forming a part of the machine, it is of course evident that an ordinary punch, of the character commonly used on the market, might be supplied separately 45 from the device and used independently thereof.

Instead of perforating the paper to secure the operating of the signaling mechanism, it is evident that I might, as previously stated, 50 emboss the paper so that the crease, groove, depression or projection might operate the circuit closing or other alarm controlling mechanism. Instead of perforating, cutting or embossing the paper, small tabs or other 55 devices might be attached thereto at the desired points. Such a tab might be in the form of a small piece of adhesive paper applied to the strip adjacent its edge and projecting beyond the latter so as to close or 60 break an electric circuit or operate a trigger or a small metal device similar to those commonly employed for securing together a plurality of sheets of paper, might be secured to the strip and used for controlling, releasing 65 or starting in operation the signaling

mechanism. Other changes and variations might be made within the scope of my invention as described in the appended claims.

In the specific form illustrated in the drawings, I have shown the supply of paper 70 in the form of a roll of such size as will provide for a considerable length of time. It is of course evident that the paper might be in separate strips each of a length sufficient for one week and it is also evident that the roller 75 15 may be entirely omitted. The paper might be drawn through one supply basket and delivered through the machine into a receiving basket. This would facilitate the picking up of the paper and writing thereon 80 at any point along the length and without releasing the clutch or rotating the drum. It is also evident that in addition to the roll shown, a separate roll may be employed upon which the paper will wind after being 85 used.

Although I have described the clutch as serving to facilitate the advancing or returning of the paper to permit the writing thereon, it is evident that this clutch may be used 90 only for securing the proper adjustment of the machine. Thus, a hole may be punched in the paper opposite the time of day on the strip opposite that shown by the clock and the clutch may then be released and the 95 drum rotated to bring this perforation up to the alarm operating mechanism. The paper will then be in proper adjustment in respect to the clock and the driving mechanism. The device, as shown, is adapted to 100 rest directly upon a table or desk, but it is of course evident that the character of the supporting means forms no part of my invention and that the side or bottom of the casing may be provided with brackets to facilitate the securing of the device directly to the wall of the room or to any other support. 105

Having thus described my invention, what I claim as new and desire to secure by Letters Patent is:

1.. A device of the character described, including a strip of paper or the like marked along its length to indicate subdivisions of time and adapted to have memoranda written or printed thereon, means for advancing 115 said strip at a substantially uniform rate, an alarm mechanism, and means for operating said alarm mechanism upon the arrival of a predetermined portion of said strip at a predetermined point.

2. A device of the character described, comprising a strip of paper sub-divided to indicate successive intervals of time and adapted to have memoranda written or printed thereon within said subdivisions, 125 means for advancing said strip at a substantially uniform rate, an alarm mechanism, means for varying the character of the strip opposite the memoranda thereon, and means for operating said alarm mecha- 130

nism upon the arrival of said memoranda bearing portion at a predetermined point in its path of travel.

3. A device of the character described, comprising a strip of paper sub-divided to indicate successive intervals of time and adapted to have memoranda concerning events to take place at or following particular predetermined times written or printed thereon, means for perforating the strip opposite such memoranda, means for advancing said strip, and means for sounding an alarm upon the arrival of the perforation at a predetermined point in its path of travel.

4. A device of the character described, comprising a strip of paper sub-divided to indicate successive intervals of time and adapted to have memoranda concerning events to take place at or following particular predetermined times written or printed thereon, means for perforating the strip opposite such memoranda, means for advancing said strip, an alarm mechanism, and means for operating said mechanism, said means being controlled by the movement of said perforation at a predetermined point in its path of travel.

5. A device of the character described, comprising a strip of paper sub-divided to indicate successive intervals of time and adapted to have memoranda concerning events to take place at or following particular predetermined times written or printed thereon, means for perforating the strip opposite such memoranda, means for advancing said strip, an alarm mechanism, and a controller for said alarm mechanism movable to effect the sounding of the alarm upon the movement of a perforation past said controller.

6. A device of the character described, comprising a strip of paper sub-divided to indicate successive intervals of time and adapted to have memoranda concerning

events to take place at or following particular predetermined times written or printed thereon, means for advancing said strip at a uniform rate, means for advancing or returning said strip independently of said last mentioned means, and means for sounding an alarm as the portion of said strip bearing said memoranda passes a predetermined point.

7. A device of the character described, comprising a strip of paper sub-divided to indicate successive intervals of time and adapted to have memoranda written or printed thereon, a drum adapted to engage with and advance said strip of paper, a source of power, driving connections therebetween, an alarm mechanism, a member for controlling said alarm mechanism and means for perforating said paper at a point at any desired distance in advance of said member, said member being movable to operative and inoperative positions as a perforation in said strip passes said controlling member.

8. A device of the character described, including a casing having a top wall, a drum within said casing for engaging with a strip of paper and advancing the latter across the top of the casing at a substantially uniform rate, said top serving to support said strip while memoranda is being written or printed thereon, means for altering the character of the paper at a point bearing a predetermined relationship to the point at which said memoranda is applied to the strip, and a signaling mechanism operated upon the arrival of said portion of altered character at a predetermined point in its path.

Signed at Louisville, in the county of Jefferson and State of Kentucky this 3rd day of December, A. D. 1914.
